UNITED STATES PATENT OFFICE.

JAMES WILLIAM DECKERT, OF OAKVILLE, CANADA.

SETTING-OUT, GLASSING, AND POLISHING MACHINE.

SPECIFICATION forming part of Letters Patent No. 789,262, dated May 9, 1905.

Application filed October 15, 1904. Serial No. 228,642.

To all whom it may concern:

Be it known that I, JAMES WILLIAM DECKERT, leather-splitter, a citizen of the United States, residing in the town of Oakville, county 5 of Halton, Province of Ontario, Canada, have invented certain new and useful Improvements in Setting-Out, Glassing, and Polishing Machines, of which the following is a specification.

My invention relates to improvements in setting-out, glassing, and polishing machines: and the objects of my invention are, first, to provide a machine of this class that will adjust itself to the different thicknesses of the 15 hide, so that thin as well as thick portions thereof will be thoroughly set out, glassed, or polished; secondly, to regulate the pressure of the hide against the cylinder; thirdly, to firmly yet yieldingly keep the hide in contact with 20 as much of the cylinder as possible, preferably one-quarter of the periphery of same, so that the hide may be thoroughly worked upon, and, fourthly, to construct an efficient machine of this class at the minimum cost; and 25 it broadly consists of a rotary cylinder and non-rotatable means constructed so as to keep thin as well as thick portions of the hide in contact with said cylinder under variable or constant pressure, and details of construction, 30 as hereinafter more particularly explained.

Figure 1 is a front side elevation of my machine. Fig. 2 is a vertical section on the line *a b*, Fig. 1. Fig. 3 is an enlarged perspective view of the means used for keeping the hide 35 in contact with the cylinder. Fig. 4 is a vertical section on the line *c d*, Fig. 2. Fig. 5 is an enlarged cross-section through one of the blocks used for keeping the hide in contact with the cylinder. Fig. 6 is a perspective view of the preferred form of bracket. Fig. 7 is a vertical section on the line *a b*, Fig. 1, showing my machine assembled for doing 40 heavy work, certain parts being removed.

In the drawings like characters of reference 45 indicate corresponding parts in each figure.

A is the bed of the machine, and *C* the head-blocks, suitably secured thereto. Suitably mounted in these head-blocks is the cylinder *D*. On one end of the shaft *E* of the said cylinder is a drive-pulley *F*.

G represents suitable tie-girdles, by means of which the head-blocks *C* are supported at their upper portions.

Although I may use any construction of cylinder in connection with my machine, I preferably use the cylinder described and claimed in my application, Serial No. 212,672, filed June 15, 1904, the patent for which is dated October 4, 1904, and numbered 771,614.

The shaft *E* is preferably held in any suitable adjustable bearings *H*.

In order to get the best possible results in working hides, it is absolutely necessary that thin as well as thick portions thereof be worked upon. For delicate work, such as 65 glassing or polishing, I firmly yet yieldingly support in the position shown relative to the cylinder *D* a series of blocks *I*, preferably made of rawhide, but which may be made of any suitable material. The edge of these 70 blocks adjacent the cylinder *D* is approximately concentric thereto, so that when the hide *J* is placed and held between same and the cylinder all portions of the hide held by said blocks will be held under varying pressure 75 in contact with said cylinder, the pressure being preferably gradually increased from point of first contact of said cylinder with the hide to point where it leaves same. As will be seen from Fig. 2, I prefer- 80 ably construct said blocks so that they will keep the portion of the hide operated upon in the preferred manner above stated in contact with at least one-quarter of the periphery of the cylinder *D*.

In order to provide for 85 the up-and-down movement of the blocks *I*, I provide a steel plate *K* and slit same for a suitable distance, so as to provide a series of fingers *l*, each one of which has suitably secured to it, as by screws *m*, one of the blocks *I*. 90 From the construction just described it will be understood that the blocks *I* will have independent movement with their fingers *l*. In case a thick portion of the hide should be held between the cylinder *D* and any of the blocks 95 *I* the said blocks and their fingers *l* will yield sufficiently, and in case a thin portion of the hide should be held between the cylinder and any of the blocks the fingers *l* will be caused to exert a force so as to keep the thin portion 100

of said hide in contact with the cylinder by means of their blocks I.

Placed underneath the steel plate K is an intermediate plate L, extending for the whole 5 length of same, but of less width than said plate, so as not to interfere with the movement of the fingers k, and underneath the plate L is another steel plate M of equal length to the plate L, but of less width than 10 same. Through the back portions of these plates and through the upper base-plate N and intermediate base-plate O pass the screws P, which secure the above-mentioned parts to the lower base-plate Q, held by any suitable 15 bearing-caps R upon the pivot-bar S, supported at its ends, as hereinafter described. The intermediate supports for said pivot-bar preferably consist of stands T, through the upper portion of which said pivot-bar passes. 20 By means of the screws t the slotted base of the said stands is secured to the bed A. By so supporting the plates K, L, and M upon each other it will be understood that their movement will not be interfered with. 25 In order to support the fingers k on their under sides and near their ends so that they may maintain the requisite pressure of the blocks I against the hide during polishing or 30 glassing, I provide a resilient foundation constructed in any suitable manner. My preferred means for this purpose consists of a rubber cushion U, suitably held by the brackets V in position upon the intermediate base-plate O. This resilient foundation will 35 permit of the necessary movement of the blocks I. In order to regulate the pressure of the blocks I against the hide, I suitably connect the front portion of the lower base-plate Q with the rock-shaft W, suitably held in the 40 head-blocks C. For this purpose my construction shown consists of connecting-rods B', the lower ends of which have bearing upon 45 the eccentrics W', secured to the rock-shaft W. By means of the socket-plate B² thereon, having bearing in the lower base-plate Q, and the slot a in said lower base-plate said connecting-rods may have movement at their upper ends, so that when the arm C', secured to 50 one end of the rock-shaft W, is moved, say, in the direction indicated by arrow, the eccentrics W' move the connecting-rods B' downward, so as to tilt the rear side of the lower base-plate Q, and thus move the fingers k and lower portions of the blocks I closer to 55 the cylinder D. By means of any suitable fastening means c the arm C' is secured to the quadrant C², (suitably secured to the machine-frame,) and thus the blocks I held in the required position. B³ represents nuts on the 60 upper end of the connecting-rods B' to keep same in position.

When the hide between the blocks I and cylinder D has been sufficiently worked, the arms C' are moved upward, thus releasing the pressure 65 of the blocks I against the hide, so that

the worked portion of the hide may be moved onto the receiving-board D', held at the required angle upon the brackets D², suitably secured to the bed A. The to-be-worked-upon portion of the hide is moved from the feeding-board D³ (suitably secured to the brackets D⁴, in turn suitably secured to the lower base-plate Q) into position between the blocks I and cylinder D and the necessary pressure given to said blocks. 70

By means of the screws d, extending through the slotted base of the brackets D², the said brackets are adjustable. 75

By means of any suitable bearing-blocks A², suitably secured to the bed of the machine, 80 the rock-shaft W is given intermediate bearing.

By means of the arm C', connecting-rods B', and means intermediate same and the blocks I the pressure of the said blocks against the 85 hide is regulated. This movement throws the upper portion i of the blocks I away from the cylinder. In order to regulate the distance of the upper portion of said blocks from the cylinder, I provide means whereby the lower 90 base-plate Q and supporting parts are moved. Each end of the pivot-bar S is held in the sliding plates U', sliding between the guide-strips U², suitably secured to the inner side of the head-blocks. Suitably secured to the outer 95 end of the sliding plates U' are brackets U³, in which have movement the adjusting-screws U⁴, which screw into the edge of said head-blocks. In order to move the blocks I toward the cylinder, the screws t are loosened and 100 the screws U⁴ turned so as to move the sliding plate U' inward, and thus, through the pivot-bar S and connected parts, give the said blocks the necessary movement. When the parts are thus adjusted, the screws t are tightened up. 105

The normal position of the blocks I is such that the lower portions of same will be closer to the cylinder than the upper portions, thus gradually increasing the pressure of the cylinder against the hide from the point where same first comes in contact therewith to the point where same leaves the hide. 110

For heavy work, such as setting out leather, I dispense with the blocks I, feeding-board D³, and brackets D⁴ and merely use the plate K and its fingers k. (See Fig. 7.) The fingers k will keep all inequalities in the thickness of the hide in contact with the cylinder. Of course when I only use the fingers k it will 115 be understood that only a small portion of the periphery of the cylinder will be in contact with the hide at any given period. By means of the parts before described for moving the blocks I to or from the cylinder it will be understood that the distance of the tongues to or from the cylinder D will also be regulated thereby. 120

I preferably support the blocks I so that the hide will be held in contact with the cylinder. 125 130

under varying pressure; but I do not confine myself to so supporting said blocks, as same may be supported so that their convex surfaces will be concentric to said cylinder.

5 As before mentioned, the blocks I may be made of any suitable material; but I preferably make same up of a plurality of pieces of rawhide i^1 and suitably secure them together, as by rivets i^2 . The ends i^3 and i^4 of said blocks are rounded, so as not to interfere with the movement of the hide.

I do not confine myself to the construction herein shown and described, as same can be altered in various ways without departing from 15 the spirit of my invention.

What I claim as my invention is—

1. The combination with a cylinder, and means for operating same, of a plurality of non-rotatable blocks approximately concentric to the cylinder for one-quarter of its periphery; a series of metal tongues to each one of which a block is secured, and means for firmly yet yieldingly keeping said tongues and blocks in position relative to said cylinder.

25 2. The combination with a cylinder, and means for operating same, of a plurality of non-rotatable blocks approximately concentric to the cylinder for one-quarter of its periphery; a series of metal tongues to each one 30 of which a block is secured; means for firmly yet yieldingly keeping said tongue and blocks in position relative to said cylinder, and means for moving said tongues and blocks to or from said cylinder.

35 3. The combination with a cylinder, and means for operating same, of a plurality of non-rotatable blocks approximately concentric to the cylinder for one-quarter of its periphery; a series of metal tongues to each one 40 of which a block is secured; means for firmly yet yieldingly keeping said tongues and blocks in position relative to said cylinder, and means for giving the said blocks and tongues the requisite up and in movement toward said cylinder.

45 4. The combination with a cylinder, and means for operating same, of a plurality of non-rotatable rawhide blocks approximately concentric to the cylinder for one-quarter of its periphery; a series of metal tongues to each of which a block is secured; a support, and a rubber cushion held upon said support and upon which said tongues rest in order that they may be firmly yet yieldingly held in position relative to said cylinder.

55 5. The combination with a cylinder, and means for operating same, of a plurality of non-rotatable rawhide blocks approximately concentric to the cylinder for one-quarter of its periphery; a series of metal tongues to each of which a block is secured; a support; a pivot-bar on which said support is held; a rubber cushion held upon said support and upon which said tongues rest in order that 60 said blocks may be firmly yet yieldingly held

in position relative to said cylinder, and means for moving said support around said pivot-bar so as to move said blocks up to or down from said cylinder.

6. The combination with a cylinder, and 70 means for operating same, of a plurality of non-rotatable rawhide blocks approximately concentric to the cylinder for one-quarter of its periphery; a series of metal tongues to each of which a block is secured; a support; 75 a pivot-bar on which said support is held; a rubber cushion held upon said support and upon which said tongues rest in order that said blocks may be firmly yet yieldingly held in position relative to said cylinder; means 80 for moving said support around said pivot-bar so as to move said blocks up to or down from said cylinder, and means for operating said pivot-bar and its support to move said blocks at right angles to said cylinder. 85

7. The combination with a cylinder, and means for operating same, of a plurality of non-rotatable rawhide blocks approximately concentric to the cylinder for one-quarter of its periphery; a metal plate provided with a 90 series of tongues extending underneath said cylinder to each one of which a block is secured; a first supporting-plate placed against under side of said plate and of less width than same; a second supporting-plate placed underneath said first supporting-plate and narrower than same; a support; a rubber cushion held upon said support and upon which said tongues rest in order that said blocks may be firmly 95 yet yieldingly held in position relative to said cylinder; a pivot-bar on which said support is held; means for moving said support and plates around said pivot-bar so as to move said blocks up to or down from said cylinder, and means for operating said pivot-bar and 100 parts supported thereby to move said blocks at right angles to said cylinder.

8. The combination with a cylinder, and means for operating same, of a plurality of non-rotatable rawhide blocks approximately 110 concentric to the cylinder for one-quarter of its periphery; a metal plate provided with a series of tongues extending underneath said cylinder to each one of which a block is secured; a first supporting-plate placed against 115 under side of said plate and of less width than same; a second supporting-plate placed underneath said first supporting-plate and narrower than same; a support; a rubber cushion held upon said support and upon which said 120 tongues rest in order that said blocks may be firmly yet yieldingly held in position relative to said cylinder; a pivot-bar on which said support is held; means for moving said support and plates around said pivot-bar so as to 125 move said blocks up to or down from said cylinder; means for operating said pivot-bar and parts supported thereby to move said blocks at right angles to said cylinder; a feeding-board supported relative to the front upper 130

ends of said blocks, and a receiving-board supported relative to the lower ends of said blocks so as to receive the finished hide therefrom.

5 9. In a machine of the class described, the combination with a series of blocks provided with concave edges; a metal plate provided with a series of tongues to the upper side of each one of which a block is secured; a pivot-bar; a support held thereon on which said plate is held, and means held on said support and upon which said tongues rest so that they may be firmly yet yieldingly held in position, of means for moving said support and said 15 blocks around said pivot-bar.

10. In a machine of the class described, the combination with a series of blocks provided with concave edges; a metal plate provided with a series of tongues to the upper side of each one of which a block is secured; a pivot-bar; a support held thereon on which said plate is held; means held on said support and upon which said tongues rest so that they may be firmly yet yieldingly held in position, of means for moving said support and said 25 blocks around said pivot-bar, and means for moving horizontally said pivot-bar, support, and blocks.

11. In a machine of the class described, the combination with a tilting support, of a series of rawhide blocks provided with concave edges; a metal plate provided with a series of metal tongues to the upper side of each one of which a block is secured; a first supporting-plate resting against under side of said metal plate but of less width than same so as not to interfere with the action of said tongues; a second supporting-plate underneath said first supporting-plate and of less width than same, 40 the said plates having free movement against each other, and screws passing through the back portions of said plates and securing them to said tilting support.

12. In a machine of the class described, the combination with a tilting support, of a series of rawhide blocks provided with concave edges; a metal plate provided with a series of metal tongues to the upper side of each one of which a block is secured; a first supporting-plate resting against under side of said metal plate but of less width than same, so as not to interfere with the action of said tongues; a second supporting-plate underneath said first supporting-plate and of less width than same, 55 the said plates having free movement against each other, and screws passing through the back portions of said plates and securing them

to said tilting support, and resilient means held by said tilting support and against the under side of said tongues so that same may 60 be firmly yet yieldingly held in position.

13. In a machine of the class described, the combination with a suitable support and a metal plate provided with a series of tongues capable of and having independent movement, 65 of a series of rawhide blocks provided with concave edges secured to the upper side of each of said tongues.

14. In a machine of the class described, the combination with a suitable support and a metal plate provided with a series of tongues capable of and having independent movement, 70 of a series of rawhide blocks provided with concave edges and rounded upper and lower ends secured to the upper side of each of said 75 tongues.

15. The combination with a cylinder, and means for operating same, of a metal plate provided with a plurality of horizontally-held tongues constructed to have movement independent of each other so as to keep thick and thin portions of the work under operation in contact with said cylinder; a first supporting-plate placed against under side of said plate and of less width than same; a second supporting-plate placed underneath said supporting-plate and of less width than same, the said plates having free movement against each other; a support; screws passing through the back portions of said plates and securing them 85 to said support, and means for moving said support so as to regulate the distance of said tongues from said cylinder.

16. The combination with a cylinder, and means for operating same, of a plurality of 90 non-rotatable blocks approximately concentric to the cylinder for one-quarter of its periphery, and a series of metal tongues to each one of which a block is secured.

17. The combination with a cylinder, and means for operating same, of a support; a series of horizontal metal tongues secured thereto so as to have free movement and underneath said cylinder, and a bed made of resilient material against which said series of metal 105 tongues rest.

In testimony whereof I have signed my name to this specification in the presence of two subscribing witnesses.

JAMES WILLIAM DECKERT.
